Inventor
Charles Edward Glander.

By his Attorney

Oscar Geier

UNITED STATES PATENT OFFICE.

CHARLES EDWARD GLANDER, OF JERSEY CITY HEIGHTS, NEW JERSEY.

TRAP-NEST.

1,270,283.

Specification of Letters Patent. Patented June 25, 1918.

Application filed May 24, 1917. Serial No. 170,613.

To all whom it may concern:

Be it known that I, CHARLES EDWARD GLANDER, a citizen of the United States, resident of Jersey City Heights, county of 5 Hudson, and State of New Jersey, have invented certain new and useful Improvements in Trap-Nests, of which the following is a specification.

This invention relates to improvements in 10 portable laying coops for poultry, and has as its special object the provision of means whereby a fowl upon entering a nest within the coop is detained therein until released; thereby enabling an accurate record 15 to be made of its performance.

Another object is to provide coops which are readily portable and which are cheap in construction from ordinary material.

These and other like objects are attained 20 by the novel construction and combination of parts hereafter described and shown in the accompanying drawings, forming a material part of this disclosure, and in which:—

25 Figure 1 is a perspective view of a laying coop made in accordance with the invention.

Fig. 2 is a fragmental vertical sectional view, the cover being raised, disclosing the 30 record carrying means.

Fig. 3 is a vertical sectional view taken on line 3—3 of Fig. 2.

Fig. 4 is a vertical sectional view taken through the center of the coop parts being 35 broken away to show the construction.

Fig. 5 is another sectional view taken in a different plane, the section being taken on line 5—5 of Fig. 4, the parts being shown in a normal raised position.

40 Fig. 6 is a similar sectional view showing the same in operative position.

Fig. 7 is an enlarged side elevational and sectional view showing the automatically operated retaining means.

45 Fig. 8 is a similar view showing the same parts after operation.

Fig. 9 is a fragmental plan view of the coop in a closed position, and

50 Fig. 10 is a similar view of the same showing the parts in a partially open position.

The invention includes a frame having

corner posts 15, adapted to rest on their lower ends upon any substantially level surface and have engaged therebetween upper 55 and lower horizontal bars, respectively 16 and 17, between which extend a plurality of vertical rods 18, forming a lattice-work or cage, so arranged as to prevent the passage of the chicken. 60

Secured on the top of the horizontal bars 16 is a rectangular structure 20 provided with a cover plate 21, secured by means of hinges 22 so as to be readily raised or lowered, a handle 23 being provided for this 65 purpose. The coop 20 is made of opaque material so as to render the interior relatively dark, a condition desirable and preferred by a hen at the time of the disposal of an egg. 70

A partial flooring or platform 25 below the coop has an extending element 26 slightly above the surface upon which the posts 15 rest and conveniently accessible to the entering fowl which passes through an 75 opening formed in the coop wall between two upright slides 28, grooved to receive a sliding frame 30, having a cross bar 31, from which extend a plurality of vertical rods 32, the upper end of the slide being joined 80 by the arcuate connecting element 33.

The entering fowl, attracted by the privacy of the coop 20, finds its way to the nest 35, supported along one edge by the hinged connections 36, and causes the nest to be 85 depressed from its normal position as indicated in Fig. 5 to that indicated in Fig. 6.

The depression of the nest exerts tension on the cord 38, the upper end of which passes over the pulley 39, and engages with 90 the plunger head 40, formed with a stem 41, normally pressed forward by the flat spring 42, so as to engage with the sliding gate 30, permitting it to fall by gravity and preventing the departure of the fowl. 95

At the same time, the oppositely disposed cord 43, passing over a similar pulley 44, is attached to another plunger 45 pressed forward by the flat spring 46, and having its extending end 47 engaged with an opening suitably formed within the plate 50, acting as a gate normally preventing entrance to the main part of the cage. 100

When the fowl has entered the nest, de-

pressing the same, both cords are pulled, permitting the gate 30 to descend and at the same time the plate 50 to drop, allowing the fowl, if so disposed to enter the main part 5 of the cage, which is provided with an extended front 52 having lattice bars 53, and containing a manually operable gate 54, comprised of bars 55 which may be withdrawn, thereby permitting the exit of the 10 fowl which may be assisted by entering the hand of an operator to raise the fowl when desired.

From the foregoing, it will be seen that a fowl once entering the gate and resting 15 its weight upon the nest will become automatically detained but permitted the freedom or run of the entire cage, and must remain therein until released manually by moving the gate 54. At the same time the 20 fowl is maintained free from interruption or intrusion.

Arranged on the lower side of the lid 21 is a card holder adapted to receive a record card 56, while a pencil 57, may be secured 25 by the cord 58, where it will always be conveniently accessible to make any records as may be desired, the face of the record bearing inscriptions or numbers indicating the individual fowl which is released and noting 30 its accomplishment.

In operation, it will be understood that after the fowl has been removed, that the entrance gate is placed in its original position, ready for the next succeeding fowl, 35 which will operate the parts automatically in the manner before described.

From the foregoing, it will be seen that a very cheap and effective device for the purpose has been described, which contains 40 no parts which may damage or frighten the fowl, and which may be readily moved and placed where desired.

Having thus described my invention, what I claim as new, and desire to secure by Letters Patent, is:—

1. In a device as described, in combination, a four-sided latticed frame, a box secured upon one corner of said frame, a platform extending alongside said box flush 50 with the bottom thereof and with its front side, but projecting beyond the opposite side of said box, a gate-way mounted upon said platform thereabove at its projecting end, a gate-way mounted at the opposite end of 55 said platform, a gate adapted to project, when in open position, below said platform, a gate adapted to project above said platform when in open position, said gates working in the respective gate-ways, means 60 for severally holding said gates in closed position, and compressible means in said box releasing said holding means whereby both gates move by gravity downwardly.

2. In a device as described, in combination, a latticed frame-work, a box secured

upon one corner thereof, a platform secured alongside of said box and projecting forwardly of one side thereof, a strip secured transversely along one edge of said platform, a pan-like member hinged at its rear end to a wall of said box and having its forward end adapted when pressed upon to rest upon said strip, a gateway arranged above said platform, a gate working therein, a locking member for holding said gate in raised position, and means operatively associated with said pan-like member and adapted, when said member is depressed, to release said locking member.

3. In a device as described, in combination, a frame, including a wall, a gate slidably mounted opposite said wall, said gate and wall having registerable openings, a bracket projecting forwardly of said wall opposite its opening, and including a pair 85 of parallel side walls and an end wall connected thereto, a pulley mounted at the lower corner of the end and side walls of said bracket, a plunger rod slidably mounted in both of said openings when they register, a shoulder formed upon said plunger and at right angles thereto and projecting above and below the same, the forward edge of the upper portion of said shoulder being beveled forwardly at an upward inclination, 90 a rope secured at one end to said plunger and passing over said pulley, the end wall of said bracket having an opening, and a leaf spring composed of a loop portion and oppositely disposed legs converging therefrom 95 and formed with outwardly-deflected terminals, one of which is seated in the last-named opening to position said spring and the other terminal inclining in the same direction as and engaging the inclined edge 100 of said shoulder to hold the latter in contact with said wall and said plunger projected in the two first-named openings.

4. In a device as described, in combination, a four-sided latticed inclosure, the bars at one side thereof being longer than those at the opposite side, a box extending transversely of said inclosure with its front side flush with the front of said inclosure and its rear side spaced from said longer bars, said 110 box providing a platform at right angles to the longer bars for a portion of its length and having its bottom open for the remainder of its length, the front side of said box being open directly above said platform, said platform projecting beyond the front side thereof, a latticed roof projecting upwardly at an inclination from the longer bars and being connected to the rear side of said box whereby to form a runway, an impact member forming a yieldable false bottom for said box, a gate-way arranged directly over the projecting end of said platform, a gateway arranged in rear of said platform, catches disposed at the upper ends 125 130

of said gate-ways, gates in said gate-ways, the front gate having an opening at its lower end, and the rear gate at its upper end, said box having openings formed opposite its catches, said rear gate being free to be lowered downwardly from said platform, said catches engaging the openings in said gates to hold the front gate in raised position and the rear gate suspended in closed position, and means controlled by said impact member whereby the catches are simultaneously released.

In testimony whereof I have affixed my signature.

CHARLES EDWARD GLANDER.
